ARTICLE FEEDER FOR SLICERS

Ernest Albert Reussenzech, Dayton, Ohio, assignor, by mesne assignments, to International Business Machines Corporation, New York, N. Y., a corporation of New York

Application May 5, 1931. Serial No. 535,138

8 Claims. (Cl. 146—102)

This case relates to detail improvements in article slicing machines.

The object of the invention is to provide novel means for gradually slowing down movement of one of the elements of the slicing machine.

Particularly the object is to provide novel means for slowing down a reciprocatable article feeder at the end of each stroke.

Further, the object is to provide novel spring means for slowing down movement of an article feeder.

Various other objects and advantages of my invention will be obvious from the following particular description of one form of mechanism embodying the invention or from an inspection of the accompanying drawing; and the invention also constitutes certain new and novel features of construction and combination of parts herein-after set forth and claimed.

20 In the drawing:

The drawing shows the feeding side of the machine in elevation.

In detail, the machine comprises a base 10 having at each end posts 11 carrying between them a rail 12. A second rail 13 is mounted on the base below the rail 12. These rails guide an article holding and feeding carriage 14 for movement to and from a disk knife 15 which may be driven through a belt 16 from a motor 17. In the operation of the machine, an article on the carriage is moved towards the gage plate 18. This may be done by one hand of the operator holding the article while the other hand is moving the carriage towards the knife. The latter cuts a slice the thickness of which is determined by the gage plate.

In order to avoid shocks to the operator as well as injury to the machine, damping means are provided for gradually and yieldably stopping the carriage at each end of its stroke. The damping means comprises a rod 19 slidably carried by depending extensions 20 and 21 of the carriage. The rod is provided with a pin 22 engageable with extension 21 to limit movement of the rod to the right relative to the extensions. The inner half of the rod 19 is formed hollow and is in effect an air dash pot within which is closely fitted and slideable a plunger 24. Within the cylinder is preferably placed a coil spring 25 to assist the air in the dash pot in resisting the plunger as the latter moves into the cylinder. A vent hole 26 is formed in the dash pot wall for allowing the trapped air to escape as plunger 24 moves into the cylinder. If desired, spring 25 may be omitted. The plunger 24 has an enlarged por-

tion 27 slidably carried by a leg 28 of the carriage. A pin 29 on the portion 27 limits movement thereof in one direction by contact with extension 28 while in the other direction movement of the plunger 24 is limited by contact of 60 the shoulder formed by the enlarged portion 27 with extension 20. At the free end of portion 27 and the outer end of rod 19, rubber bumpers 30 are provided to contact the posts 11. These bumpers prevent direct contact between the 65 metal parts of the carriage and posts 11. The bumpers also absorb to some extent the shock of impact between these parts but are not capable of preventing the abrupt stopping of the carriage at the end of each stroke.

Near the end of the forward movement of the carriage towards the knife, the end of rod 19 engages the right hand post 11 which thereby stops the rod. The carriage, however, continues to move, extension 28 engaging pin 29 of the portion 70 27 to move the plunger 24 into the dash pot portion of rod 19 thereby compressing the air within the dash pot which slowly escapes through vent hole 26. Spring 25 is also compressed by the plunger. In combination, the spring and the 75 trapped air in the dash pot slow down the movement of the carriage. The movement of plunger 24 into the tubular, dash-pot portion of rod 19 is limited by engagement of the shoulder at the right hand end of portion 27 with the free end 80 of the tubular portion of rod 19. When the carriage is on its return stroke, the plunger portion 27 is stopped by post 11 while the carriage continues to move rod 19 thereby compressing the air in the dash pot portion and the spring to 85 slow down the return movement of the carriage. The movement of rod 19 to the left, on the return stroke of the carriage, after bumper 30 engages 90 left hand post 11 is limited by engagement of the free end of the tubular portion of rod 19 with the right hand shoulder of rod 27. When the carriage is in an intermediate position, spring 25 holds pin 22 on rod 19 against extension 21 and pin 29 of rod 27 against extension 28.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims:

70

75

80

85

90

100

105

110

1. In a machine of the class described, manually operable means having a forward and return stroke, stops to limit the extent of each stroke, and a device for slowing down the movement of the said means near the end of each stroke, said device including a pair of coacting members carried by aforesaid means, one of said members engaging a stop at the end of the forward stroke and the other member engaging a stop at the end of the return stroke, said means continuing to move one member towards and against resistance of the other member after the latter has been engaged with a stop. 80
2. In a machine of the class described, a reciprocatable device, means for mounting the device for reciprocatable movement, stops, one for limiting the forward and the other the return stroke of the device, a member movably mounted on said device for engaging one of the stops near the end of the forward stroke to remain stationary while said device continues to move to complete the forward stroke, another member movably mounted on said device and coacting with the first-named member after the latter has been held stationary by its associated stop to dampen the movement of said device in completing the forward stroke, the second-named member engaging the other of the stops near the end of the return stroke of the device to be held stationary while the device continues to move to complete the return stroke, the first-named member coacting with the second-named member after the latter is stationary to dampen the movement of the device in completing its return stroke. 90
3. In a machine such as defined in claim 2, one of said members comprising a plunger and the other a dash pot in which the plunger is movable to form a single dash pot dampening means for dampening both strokes of the reciprocatable device. 100
4. In a machine such as defined in claim 2, the members being each slidably mounted on the device and in damping coaction with each other. 105
5. In a machine such as defined in claim 2, and means for normally urging the elements apart, the members approaching each other against resistance of said means after one of said members has been held stationary by its stop to dampen continued movement of the device in completing a stroke. 110
6. In a machine such as defined in claim 2, and resilient means interposed between said members and resisting relative movement of said members upon one of the latter being held stationary and the other continuing to move with the device when the latter completes a stroke whereby the resilient means dampens the final movement of the device when completing a stroke. 115
7. In a machine such as defined in claim 2, means for normally holding the members separated and furthest apart during the free movement of the device between the ends of a stroke, and coacting means on the members and said device for limiting the separation of said members. 120
8. In a machine of the class described, an article support, means for mounting the support for reciprocation, stops, one for limiting the forward stroke of the support and the other for limiting the return stroke of the support, a spring carried by the support below its article supporting surface, an element engaging one of the stops near the end of the forward stroke of the support and cooperating with the spring to compress said spring to dampen the movement of the support in completing the forward stroke, and an element engaging the other of the stops near the end of the return stroke of the support to cooperate with the same spring for compressing the latter and dampening movement of the support in completing its return stroke. 125
